UNITED STATES PATENT OFFICE.

JOHN J. LICHTER, OF ST. LOUIS, MISSOURI.

HEAT-TREATING APPARATUS.

1,112,074.

Specification of Letters Patent. Patented Sept. 29, 1914.

Application filed May 7, 1914. Serial No. 837,040.

To all whom it may concern:

Be it known that I, JOHN J. LICHTER, a citizen of the United States, residing at St. Louis, Missouri, have invented a certain new and useful Improvement in Heat-Treating Apparatus, of which the following is a full, clear, and exact description, such as will enable others skilled in the art to which it appertains to make and use the same.

This invention relates to apparatus used in the heat treatment of metals and other substances.

One object of my invention is to provide a heat treating apparatus that comprises a furnace of novel design and also a dipping tank which is arranged in such a position with relation to the furnace that the material being treated can be removed from the furnace chamber and quenched in the bath in the dipping tank, without liability of breaking the sealing ledges on the side walls of the furnace chamber, or exposing the material to the atmosphere, and thus causing it to cool off and oxidize before it is quenched.

Another object is to provide an apparatus of the character described, in which the roof of the furnace is so designed that it does not exert side thrusts on the side walls of the furnace, and furthermore, insures a uniform and even distribution of heat across the entire width of the furnace chamber.

Another object is to provide a heat-treating furnace, in which the flues for the escape of the waste gases are arranged in such a manner that an even distribution of heat is insured throughout the entire length of the furnace chamber, and still another object is to provide an apparatus of the character described, in which the means for immersing the material in the quenching bath consists of a cradle that travels on tracks supported by the side walls of the dipping tank and arranged vertically or in an inclined position at practically any angle from 0 to 90°.

Figure 1 of the drawings is a vertical, longitudinal, sectional view of an apparatus constructed in accordance with my invention. Fig. 2 is a vertical, transverse sectional view taken on the line 2—2 of Fig. 1; and Fig. 3 is a horizontal sectional view taken on the line 3—3 of Fig. 1.

Referring to the drawings which illustrate the preferred form of my invention, A designates a heating furnace provided

at one or both ends with doors 1, of any suitable type, and having fire pits 2 arranged at one side of the furnace chamber 3 so that the fire gases will flow transversely across the furnace chamber and escape through waste flues 4 whose lower ends communicate with a horizontally disposed flue 5 that leads to a stack 6, as shown in Figs. 2 and 3. The flues 4 for the waste gases preferably extend throughout the entire length of the furnace, as shown in Fig. 3, so that the heat will be distributed uniformly and evenly throughout the entire length of the furnace chamber 3, and the roof of the furnace chamber is flat or disposed in a horizontal plane, as shown in Fig. 2, so as to cause the heat to be distributed uniformly and evenly across the entire width of the furnace chamber. I prefer to form said roof in such a manner that it will not exert side thrusts on the side walls 7 of the furnace, and in the embodiment of my invention herein shown said roof is composed of tiles 8 that are carried by I-beams 9 that extend longitudinally of the furnace, and which are supported or carried by I-beams or supports 10 that extend transversely of the furnace and rest upon the upper edges of the side walls 7.

The material or articles to be treated are placed upon a truck B, which is thereafter run into the furnace A, said truck being provided with a refractory top surface or floor 11, that forms the bottom of the furnace chamber 3. The longitudinal edge portions of the floor or platform of the truck B project laterally underneath horizontally disposed ledges 12 on the side walls of the furnace chamber, and the end portions of said platform project under the doors of the furnace. After the truck has been arranged in operative position in the furnace, sand or some other suitable material is packed between the ledges 12 and the refractory top surface 11 of the truck and in the joints at the lower edges of the door, so as to seal the furnace chamber.

A dipping tank C, that contains a quenching bath 13, is located underneath the furnace and means are provided for lowering the truck B with the material or articles thereon directly into said quenching bath after said material or articles have been heated to a predetermined temperature in the furnace A, thus eliminating the possi-

bility of the articles cooling off or oxidizing before they are quenched, and also eliminating the possibility of breaking the sealing ledges on the side walls of the furnace, as 5 might occur if the truck was withdrawn from the furnace chamber horizontally or moved longitudinally of the sealing ledges.

It is immaterial so far as my broad idea is concerned, what particular means is employed for lowering the truck B into the 10 quenching bath, but I prefer to provide the dipping tank with a cradle D that travels in an inclined plane on tracks 14 which are preferably supported by ledges 15 on the 15 side walls of the dipping tank, as shown in Fig. 2, said tracks being arranged at any desired angle, from a small angle to the horizontal, to practically a vertical line or 90°. The cradle D is so designed that the top portion 20 of same is horizontal, and it is provided with tracks 16 for the truck B that align with the tracks 17 on which the truck B rests while it is being loaded. The dipping tank is long enough to permit the cradle to 25 travel far enough to cause the truck B, with its contents, to be completely submerged in the quenching bath and suitable means are provided for pulling the cradle up and down the incline on which it travels, the means 30 herein shown for this purpose consisting of a hydraulic lift 18 whose cable is connected to one end of the cradle D, as shown in Fig. 1.

One advantage of an apparatus of the 35 construction above described is, that the dipping tank that contains the quenching bath is combined with the furnace and is located in such a position with relation to the furnace that the material being treated can be 40 quenched without exposing it to the atmosphere after it is removed from the furnace chamber, and without liability of breaking the sealing ledges on the side walls of the furnace, this latter feature, of course, being 45 due to the fact that the truck on which the material rests while it is being heated drops downwardly away from the sealing ledges when the truck is being removed from the furnace chamber. The roof of the furnace 50 is flat and disposed in a horizontal plane so

that all points of the roof will be the same distance from the floor or bottom of the furnace chamber on which the material being heated rests, consequently, the heat will be distributed uniformly and evenly across the 55 entire width of the furnace chamber. By suspending the roof from members that rest upon the side walls of the furnace I eliminate side thrusts on the side walls of the furnace, and by providing waste gas flues 60 throughout the entire length of the furnace I obtain a uniform and even distribution of heat throughout the entire length of the furnace chamber.

In addition to the desirable features above 65 mentioned, an apparatus of the character described requires very little power to operate the device which lowers and raises the truck B into and out of the quenching bath, owing to the fact that the cradle D travels in 70 an inclined plane.

Having thus described my invention, what I claim is:

1. An apparatus for treating metals and other substances, comprising a heating furnace, a dipping tank located underneath the chamber of the furnace, a truck or carrier whose edge portions project under sealing ledges on the side walls of the furnace chamber, and means for moving said truck downward and in an inclined plane into said dipping tank.

2. An apparatus for treating metals and other substances, comprising a heating furnace, a dipping tank arranged under the 85 chamber of the furnace and provided with inclined tracks, a cradle traveling on said tracks, and a truck or carrier that is adapted to be run onto said cradle so as to form the bottom of the chamber of said furnace during the operation of heating the substance being treated.

In testimony whereof I hereunto affix my signature in the presence of two witnesses, this fourth day of May, 1914.

JOHN J. LICHTER.
